UNITED STATES PATENT OFFICE.

HARRY BECKER, OF BALTIMORE, MARYLAND.

OUTLET-BOX.

No. 877,880.

Specification of Letters Patent.

Patented Jan. 28, 1908.

Application filed February 1, 1907. Serial No. 355,261.

To all whom it may concern:

Be it known that I, HARRY BECKER, a citizen of the United States, residing at the city of Baltimore, in the county of Baltimore City and State of Maryland, have invented new and useful Improvements in Outlet-Boxes, of which the following is a specification.

My invention relates to outlet boxes for electric wiring, and more particularly to that class of box which is designed for use in place of the porcelain tube formerly employed.

The object of my invention is to produce a device of the character described of a type similar to what is generally in use, but having many advantages thereover.

With the above and other objects in view, my invention consists in the construction hereinafter described and shown in the accompanying drawing, in which,

20 Figure 1 is a side elevation showing my improved outlet box in use. Fig. 2 is an inverted plan view of the same, a section being taken as indicated by line 2—2 of Fig. 1 looking in the direction of the arrow. Fig. 3 is a 25 central vertical section on an enlarged scale of the box itself.

Referring to the drawings in detail, and particularly to Fig. 1, it will be seen that the outlet boxes 1, 1 are attached to the ends of 30 a pipe 3 of iron or other suitable material which passes through the wall 4 of a building, and can be rotated about the pipe as an axis to secure desired adjustments.

2 indicates the leads or wires which extend 35 from any suitable insulators or supports arranged near the outlet box so as to take the strain off of the box as is well known.

As clearly shown in Fig. 3 my improved outlet box consists of a cylindrical casing 8 provided with a neck 5 extending from the side thereof, said cylindrical casing terminating in the upstanding flange 7. The neck 5 is internally screw-threaded as at 6 for the purpose of attaching the same to the pipe 3 40 as shown in Fig. 1. The casing 8 is provided with an internally projecting annular flange 9 lying in a plane at right angles to the sides of the cylinder, and the upstanding flange 7 is internally screw threaded as at 14. The

casing 8 is preferably formed of cast-iron or other strong and wear resisting material.

Resting against the flange 9 is a bushing 10 provided with a collar 11 around its inner edge, and surrounding the bushing 10 is a sleeve or ring 13, the inner end of which takes 55 against the collar 11. The outer edge of said ring is preferably roughened or corrugated as at 15 to provide a hand-hold. The members 16 and 13 are formed of an insulating material such as porcelain, hard rubber or 60 other suitable substance, and the bushing 10 is provided in its face with holes 12 for the reception of the wires 2. The ring 13 may in some instances advantageously be constructed of metal. 65

It will be seen that in assembling the parts the bushing 10 is placed against the flange 9 and then the ring 13 is screwed down over the same and securely holds it in place, while at the same time permitting it to turn or 70 swivel freely. The object of this construction is clearly shown in Fig. 2. Where the wires extend as shown in full lines, the holes 12 will occupy the position shown, but where the wires approach the outlet box from some 75 other direction as shown in dotted lines at 2', the bushing 10 may readily be turned and adjusted so as to bring the holes 12 into such position as will adapt them to hold the wires properly spaced. I regard this feature of 80 my invention, as heretofore it has been necessary to employ two different styles of outlet boxes according to whether the wires extend approximately parallel with or perpendicular to the face of the wall. With the present construction, it is obvious that wires approaching from any angle whatever can be 85 readily accommodated.

A further advantage of my construction 90 resides in the fact that no screws or other fastening devices whatever are employed, thereby greatly adding to the convenience and simplicity of the device.

It is thought the many advantages of my 95 invention will be readily appreciated by those skilled in the art.

Having thus described my invention, what

I claim as new and desire to secure by Letters-Patent, is:

1. An outlet box comprising a cylindrical casing, an annular flange extending from the inner walls thereof, a ring screwed into the end of said casing, and an insulating bushing held between said flange and said ring so as to swivel freely.
2. In an outlet box, an insulating perfo-

rated bushing, and a screw threaded ring surrounding said bushing and within which said bushing is free to turn. 10

In testimony whereof, I affix my signature in presence of two witnesses.

HARRY BECKER.
